UNITED STATES PATENT OFFICE

163,620

COMBINED CAKE PLATE AND ORNAMENT
THEREFOR

Marguerite V. McMonagle, Green Bay, Wis.

Application October 22, 1948, Serial No. 149,237

Term of patent 7 years

(Cl. D29—1)

To all whom it may concern:

Be it known that I, Marguerite V. McMonagle, a citizen of the United States, residing at Green Bay, in the county of Brown and State of Wisconsin, have invented a new, original, and ornamental Design for a Combined Cake Plate and Ornament Therefor, of which the following is a specification, reference being had to the accompanying drawings, forming a part thereof.

In the drawings:

Fig. 1 is a plan view of a combined cake plate and ornament therefor with a portion thereof broken away; and

Fig. 2 is a side elevational view thereof showing my new design. The back of the cake plate and the ornament therefor is identical with the front. The cake shown in broken line in Fig. 2 is for illustrative purposes only.

I claim:

The ornamental design for a combined cake

plate and ornament therefor, as shown and described.

MARGUERITE V. McMONAGLE.
